SIGN

William B. Greenlee, Denver, Colo.

Application August 28, 1934, Serial No. 741,818

13 Claims. (Cl. 40—130)

My invention relates to illuminated signs and a method of illuminating same, and more particularly to signs generally designated as neon signs.

It is an object of the present invention to provide a sign composed of non-connected neon tube units which are collectively illuminated.

Another object of my invention resides in the provision of a sign having interchangeable, non-connected neon tube units in the form of letters, symbols and the like, to permit variations in its subject as desired.

Still another object of the invention resides in a novel method of transmitting high frequency current to emit impulses which are indirectly applied in simultaneously energizing a plurality of non-connected neon tube units.

Other objects reside in novel combinations and arrangements of parts as will more fully appear in the course of the following description.

20 Referring now to the drawing in the several views of which like parts have been similarly designated, and in which,

Figure 1 represents a face view of a sign bearing a word formed by an arrangement of interchangeable tube units.

Figure 2 is a section taken along the line 2—2, Figure 1, and including the electric circuit employed to energize the tube units.

Figure 3 is a fragmentary face view of a modification of the invention,

Figure 4 is a section taken along the line 4—4, Figure 3, and

Figure 5 is an enlarged fragmentary section taken along the line 2—2, Figure 1.

35 The sign illustrated in Figure 1 comprises a frame 6 of suitable material and design. A conductive plate 7 is supported in the frame, and may be utilized as the back of the frame, if desired.

A plate 8 of di-electric material is held in the frame 6 and is spaced from conductive plate 7, as indicated at 9. A series of apertures or pockets 10 extend from the space 9 through plate 8 for a purpose to be hereinafter described.

40 Neon tube units 12 shaped to represent characters, letters, symbols or the like are held upon an exposed face of plate 8 by hooks 14 of celluloid or some similar transparent insulating material having connections 13 with the units. Each tube unit 12 is in disconnected relation with the other tube units of the sign, to facilitate interchange of the various characters. The hook and pocket arrangement permits ready removal and installation during rearrangement of the tube units. When the sign is to be used for a rather permanent legend only the necessary holding hooks

are furnished and they can, of course, be changed or rearranged whenever the occasion may arise, by removal of the back plate 7. When the sign is to be used for frequently changed legends, as for a theater, each aperture or pocket 10 is 5 equipped with a holding hook 14 so that the legend can be changed very readily by removal and insertion of the characters in the holding hooks. The connections 13 are flexible to permit this change with a minimum of effort.

10 It will be understood from the foregoing that the design or legend formed by a series of tube units is subject to change at the will of the user of the sign, and any such changes may be readily effected without removal of the sign from its 15 place of installation.

A protective plate 15 of glass or other transparent material may be placed over the exposed face of the sign, if desired, and lugs 16, or other suitable fastening means are employed in holding 20 the glass in place.

The conductive plate 7 is charged with high frequency current in the following manner. Current from a suitable source 17 is conducted through a transformer 18 to a high frequency 25 vibrator 19 and the impulses emitted thereby are conducted to a binding post 20 in contact with the plate.

It will be observed that the neon tube units 12 are not held in direct contact with the plate 7, 30 but need only be in energy transmitting adjacency to the same. The high frequency current entering the plate emits waves which energize all of the tubes simultaneously which thereupon become luminous.

35 The modification of the invention illustrated in Figures 3 and 4 employs the same principle of operation but differs in structural arrangement. The exposed face of the back plate 8 contains rows of aligned perforations, providing sockets 21 40 to receive individual neon tubes 22.

It is to be understood that both the tube units 12 and the tubes 22 may be filled with gases which display different colors when the same become luminous. Since this practice is well-known in 45 the art, no further description appears necessary.

The tubes 22 may be selectively disposed in the sockets 21 to form letters, symbols, designs and the like, and it is readily apparent that the tubes may be removed and rearranged at will.

50 The high frequency circuit illustrated in Figure 2 may be described as follows: commencing with the source 17, through conductor 23 to vibrator 19, through conductor 24 to primary coil 25 of transformer 18 and then through conductor 55

26 to source 17. When the aforementioned circuit is closed, secondary coil 27 of transformer 18 is energized thereby and the high frequency impulses from secondary coil 27 flow through conductor 28 to binding post 29 and thence to conductive plate 7.

5 After the sign is installed with the neon tube units arranged to form any desired legend in the manner already described, the plate 7 is connected in the circuit illustrated in Figure 2.

10 When the circuit is closed, the high frequency current, with which the plate 7 is charged, emits waves which energize the neon tube units 12, or the tubes 22. The tube units or tubes thereupon 15 become luminous and, the legend is displayed in a manner well-known in the art.

15 Changes and modifications may be availed of within the spirit and scope of the invention as defined in the hereunto appended claims.

20 What I claim and desire to secure by Letters Patent is:

1. A sign comprising a frame, a conductive plate in the frame, an apertured di-electric plate in the frame, a neon tube unit having means for 25 its suspension in an aperture of the di-electric plate in energy transmitting adjacency to the conductive plate, and a source of high frequency current in circuit transmitting connection with the conductive plate for illumination of the unit.

2. A sign comprising a frame, a conductive plate in the frame, an apertured di-electric plate in the frame, a plurality of neon tube units having means for their suspension in apertures of said 35 di-electric plate in energy transmitting adjacency to the conductive plate, and a source of high frequency current in circuit transmitting connection with the conductive plate for the illumination of the units simultaneously, the 40 units being in disconnected relation to each other.

3. A sign comprising a frame, a conductive plate in the frame, a di-electric plate in the frame having a plurality of sockets to receive 45 neon tubes, neon tubes fitted in the sockets in energy transmitting adjacency to the conductive plate, and a source of high frequency energy in circuit transmitting connection with the conductive plate for the illumination of the units simultaneously, the units being in disconnected relation to each other.

4. A sign comprising a frame, a conductive plate in the frame, an apertured di-electric plate in the frame, a neon tube unit having 55 means for its suspension in an aperture of the di-electric plate, inclusive of a transparent connection, holding the unit in energy transmitting adjacency to the conductive plate, and a source of high frequency current in circuit transmitting connection with the conductive plate for illumination of the unit.

5. An interchangeable illuminated sign comprising in combination, a conductive plate, substantially coextensive with the sign, a source of 65 high frequency current having one pole connected with the plate for producing a field of electrical energy about the same, a perforated lamp supporting plate located adjacent one side of the conductive plate, within the energy field, 70 and neon-type lamps having supporting means for engaging the openings in the supporting plate.

6. An interchangeable illuminated sign comprising in combination, a conductive plate, substantially co-extensive with the sign, a source of high frequency current having one pole connected with the plate for producing a field of 5 electrical energy about the same, a lamp supporting plate of dielectric material supported adjacent one side of the conductive plate, within the energy field, a plurality of neon-type lamps, and means for interchangeably attaching the 10 lamps to the dielectric plate.

7. A sign comprising a conductive plate, an apertured lamp supporting plate positioned adjacent the conductive plate, a neon tube unit having means for its suspension in an aperture 15 of the supporting plate, and a source of high frequency current having one terminal connected with the conductive plate for producing an energy field which envelopes the lamps and sets up a glow therein.

20 8. A sign comprising a conductive plate, a source of high frequency current in single pole connection with said plate for producing a field of electric energy about the same, a plate of dielectric material located adjacent the conductive plate, within the energy field, and a neon-type lamp supported on the dielectric plate.

25 9. A sign comprising an electrically conductive plate, a source of high frequency current in single pole connection with said plate for producing a field of electric energy about the same, a plate of dielectric material supported adjacent the conductive plate, within the energy field, a neon-type lamp, and means for holding the lamp on the dielectric plate.

30 10. A sign comprising a conductive plate, a plate of dielectric material positioned adjacent the conductive plate, the dielectric plate having a plurality of sockets arranged in rows, neon-type lamps arranged in the sockets to form a design, 40 and a source of high frequency current having one terminal connected with the conductive plate, for producing an energy field which envelopes the lamps and sets up a glow therein.

35 11. A sign comprising a conductive plate, a plate of dielectric material positioned adjacent the conductive plate, a plurality of lamp supports arranged in rows on the dielectric plate, neon-type lamps held by the supports in a selective design, and a source of high frequency current having one terminal connected with the conductive plate, for producing an energy field which envelopes the lamps and sets up a glow therein.

40 12. A sign comprising a conductive plate, a plate of dielectric material positioned adjacent the conductive plate, a plurality of lamp supports arranged in rows on the dielectric plate, neon-type lamps held by the supports in a selective design, with various lamps being adapted to 45 display different colors when energized.

45 13. A sign comprising a conductive plate, a source of high frequency current having one pole connected with said plate for producing a field of electric energy about the same, a plate of dielectric material adjacent the conductive plate within the energy field, and two neon-type lamps on the dielectric plate, each of which is adapted to 50 display a different color when energized.

70
